LEHR LOADER

William L. McNamara, Lancaster, Ohio, and James McFee, Camp Cooke, Calif., assignors to Anchor Hocking Glass Corporation, Lancaster, Ohio, a corporation of Delaware

Application August 17, 1942, Serial No. 455,136

9 Claims. (Cl. 198—31)

Our invention relates to a lehr loader. It has to do, more particularly, with that type of lehr loader commonly known in the art as the "pusher bar" type.

In the art, it is customary to provide pusher bar lehr loaders for receiving glassware from forming machines and transferring the ware to an annealing lehr. The articles are removed from the forming machine and are placed in an upright position on a belt conveyer which conveys them to a cross conveyer extending across the front end of the lehr. Automatic means is provided for transferring the articles to the cross conveyer which carries them in a row across the front of the lehr. They are then transferred, a row at a time, to the lehr conveyer by means of a pusher bar which is properly moved to engage the row of articles and push them off the cross conveyer and onto the lehr conveyer.

In the prior art, the main movements have been imparted to the pusher bar by means of air cylinder and piston units. To operate these cylinder and piston units requires considerable air. This is therefore an expensive way of moving the pusher bar and is particularly undesirable where the air supply in the glass plant is limited. Furthermore, variations in air supply produce variations in the movement of the pusher bar. Another disadvantage of prior art lehr-loading apparatus has resided in the fact that the lehr loaders are not capable of handling a wide variety of sizes and shapes of ware and cannot be readily adjusted for different sizes and shapes of ware. Other disadvantages have been encountered with the prior art lehr-loading apparatus.

One of the objects of our invention is to provide a lehr loader of the pusher bar type which is of such a nature that it can readily handle glassware of practically all shapes and sizes.

Another object of our invention is to provide a lehr loader which may be quickly and easily adjusted to make it suitable for use with ware of various sizes and shapes.

Another object of our invention is to provide a lehr loader of the pusher bar type which is of such a nature that the mechanism for imparting the movements to the pusher bar is mainly mechanically operated thereby requiring a minimum amount of air.

In its preferred form our invention contemplates the provision of lehr loading apparatus comprising a continuously moving conveyer which receives the ware in upright position from the forming machine and conducts it in a single line to a continuously moving cross conveyer ex-

tending across the front end of the lehr. Automatic means is provided for transferring the articles to the cross conveyer in upright position and properly spacing them on the cross conveyer and to form a row of closely spaced articles extending across the front of the lehr. A pusher bar is associated with the cross conveyer and is moved from a position behind the row of articles on the cross conveyer into engagement therewith and then horizontally over the cross conveyer. This serves to push the row of articles from the continuously moving cross conveyer onto the lehr conveyer. The pusher bar, when it reaches the extent of its forward movement over the cross conveyer, is then moved vertically and rearwardly in such a manner that it will miss the articles on the cross conveyer which are being moved into position in front of the lehr. The pusher bar is then moved rearwardly and downwardly into position behind the new row of articles on the cross conveyer. The movement of the pusher bar is intermittent but is timed with the movement of the cross conveyer. Furthermore, the movement of the pusher bar is accomplished mainly by mechanical means.

The preferred embodiment of our invention is illustrated in the accompanying drawings wherein similar characters of reference designate corresponding parts and wherein:

Figure 1 is a front elevational view of lehr loading apparatus constructed according to our invention.

Figure 2 is a top plan view of the apparatus shown in Figure 1.

Figure 3 is a side elevational view of the apparatus shown in Figures 1 and 2.

Figure 4 is a perspective view of the means provided for automatically transferring the ware from the conveyer which receives the ware from the forming machine to the cross conveyer disposed in front of the lehr.

Figure 5 is an enlarged top plan view, partly broken away, of the structure shown in Figure 4.

Figure 6 is a vertical sectional view taken substantially along line 6—6 of Figure 5.

Figure 7 is a vertical sectional view taken substantially along line 7—7 of Figure 5.

Figure 8 is a top plan view illustrating the pusher bar moving mechanism.

Figure 9 is a rear view of the structure shown in Figure 8.

Figure 10 is a longitudinal vertical sectional view taken substantially along line 10—10 of Figure 8.

Figure 11 is a detail, partly in vertical section

and partly in elevation, of timing means employed for timing movement of the pusher bar.

Figure 12 is a top plan view, partly broken away, of the structure shown in Figure 11.

Figure 13 is a view, mainly in vertical section, of clutch mechanism which we employ for controlling movement of the pusher bar.

Figure 14 is a vertical sectional view taken substantially along line 14—14 of Figure 13.

Figure 15 is a schematic view, in perspective, of the operating mechanism of our apparatus.

Figure 16 is a top plan view illustrating different means for transferring ware from the conveyer which runs from the forming machine to the cross conveyer.

Figure 17 is an enlarged view, mainly in vertical section, taken substantially along line 17—17 of Figure 16.

With reference to the drawings, we illustrate a continuously moving conveyer 1 which is adapted to receive the articles in upright position after they are removed from the forming machine. This conveyer 1 is carried by a suitable supporting frame 2 and is driven in any suitable manner. The conveyer 1 is adapted to convey the ware to a point adjacent one end of the cross conveyer 3 of our lehr loading apparatus. The cross conveyer 3 is supported by a frame 4 and extends across the front thereof. This frame 4, as will later appear, supports all portions of our apparatus. The frame 4 is so positioned that the conveyers 1 and 3 are associated with each other in the manner illustrated best in Figure 2 and the cross conveyer 3 extends across the front of a lehr 5. The lehr 5 includes a conveyer belt 6 which projects therefrom in the usual manner. Our apparatus is not connected to the lehr 5 or the conveyer 1 and, therefore, our entire unit can be moved away from the units 1 and 5 whenever desired.

The frame 4 is made up of suitable angle irons and beams and is provided with leveling jacks 7 of the screw type on each of its legs. The cross conveyer 3 is carried at the front of the frame 4 intermediate the height thereof. To support the cross conveyer 3 a transversely extending angle member 8 (Figures 6 and 10) is bolted to the front vertical legs of the frame 4 intermediate the height thereof. The angle member 8 extends the full width of frame 4 and projects forwardly from the frame and carries a pair of angle brackets 9 (Figure 1) which are bolted thereto. The upstanding flange of each of these brackets 9 is bolted to a unit 10 which serves as a support for the conveyer 3. This unit 10 comprises a pair of elongated angle beams 11, the vertical flanges of which are secured together in parallel spaced relationship by means of spacers 12 which are suitably secured thereto at longitudinally spaced intervals. The horizontal flanges 13 of these beams 11 serve as supports over which the upper flight of the chain belt 14 of the conveyer 3 slides, it being apparent that the chain belt 14 extends the full width of the space between members 11 and overlaps the flanges 13 thereof as shown in Figure 10. The beams 11 extend a substantial distance beyond each side of frame 4.

The chain belt 14 is an endless belt of any suitable type. As shown best in Figures 1, 2, 6 and 7, the chain belt 14 passes around and is adapted to be driven by sprockets 15 and 16 supported on opposite ends of the supporting unit 10. The sprocket 15 is rotatably carried by a shaft 17 which is disposed transversely of the beams 11 (Figures 6 and 17). The forward end of this shaft

is rotatably carried in a bearing 18 secured to the forward beam 11. The rear end of this shaft is rotatably carried in a ball bearing 19 supported by the rear beam 11. The gear 15 is keyed on the shaft 17 and is maintained properly spaced relative to members 11 by means of a set screw 20. The rear end of shaft 17 projects into the gear unit 21.

This gear unit 21 has a housing which is bolted to the rear beam 11 by means of bolts 22. This gear unit includes a bevel gear 23 keyed on the rear end of the shaft 17. This gear 23 meshes with a bevel pinion 24. This bevel pinion 24 is keyed on the end of a shaft 25. The shaft 25 (Figures 1, 2 and 15) is adapted to be selectively connected to or disconnected from a shaft 26 by means of a jaw clutch 27. This jaw clutch may be actuated by any suitable control member. The shaft 26 extends parallel to the rear beam 11 (Figure 2). It is supported by a plurality of bearing members 28 (Figures 1 and 2) which are bolted to the upper surface of the angle member 8. This shaft extends the full width of the frame 4 and a substantial distance beyond each side thereof. The sprocket 16 is driven in exactly the same manner as the sprocket 15. It is driven by a gear unit 29 supported by the rear beam 11 adjacent the sprocket 16. This gear unit 29 has a shaft 30 projecting therefrom which may be selectively connected to or disconnected from the shaft 26 by means of a jaw clutch 31.

It will be apparent that when the jaw clutch 27 is engaged and the clutch 31 is disengaged, the upper flight of the conveyer belt 14 will travel toward the right (Figures 1 and 2) when the shaft 26 is driven. On the other hand, if the jaw clutch 27 is disengaged and the jaw clutch 31 is engaged, the upper flight of the conveyer belt will travel toward the left when the shaft 26 is rotated. This arrangement is desirable so that the apparatus may receive articles from a conveyer unit provided at either side of our apparatus. As shown by dotted lines in Figure 2, the unit 1 could be positioned on the right-hand side of our apparatus rather than the left-hand side. The shaft 26 has a large sprocket 32 keyed thereto substantially midway between the ends thereof, as shown best in Figures 1, 2 and 15. This sprocket is driven by a chain 33 which passes around a sprocket 34 spaced below and rearwardly of the sprocket 32. The sprocket 34 is keyed on a shaft 35 extending from a gear unit 36. This unit 36 is supported on a horizontal plate 37 (Figure 1). This plate 37 is secured to the frame 4 at a suitable location spaced below the conveyer unit 3. The gear unit 36 is driven by a second gear unit 38 through the medium of a shaft 39. Both of the gear units 36 and 38 may be variable speed gear units of a suitable type. The gear unit 38 is also supported by the plate 37. The gear unit 38 is driven through the medium of a shaft 40 extending therefrom. This shaft 40 has a sprocket 41 keyed thereto which is driven by a sprocket chain 42 that passes around a sprocket 43 keyed on the drive shaft of an electric motor 44. This motor 44 is also supported by the plate 37. Thus, when the motor 44 is energized and either of the clutches 27 or 31 is engaged, the conveyer chain belt will be moved continuously.

In order to transfer glass articles from the conveyer 1 to the conveyer unit 3, we provide a spotter wheel unit 45 at either end of the conveyer unit 3 depending upon the location of the conveyer unit 1. In Figures 1 and 2 we have illus-

trated the unit 45 located at the left-hand side of our apparatus but it can be in position at the other side of our apparatus. This unit 45 is illustrated best in Figures 1, 2, 4, 5, 6 and 7. The unit 45 is supported on the end of a plate 46 which is carried by the frame 4. This plate 46 extends a substantial distance beyond each side of the frame 4. It is supported by angle members 47 which are secured to the frame 4 and extend transversely of the plate 46. The outer ends of the plate 46 are supported by angularly disposed supports 48 which have their upper ends secured to the lower surface of the plate 46 and their lower ends secured to the plate 37 carried by the frame 4.

The unit 45 comprises a vertically disposed sleeve 49 which has a flanged foot bolted to the upper surface of the plate 46 by bolts 50, as shown in Figure 6. A vertically disposed shaft 51 is keyed in the sleeve 49. The extreme upper end of the shaft 51 has a reduced portion 52 which supports a disk-like cam member 53. This member 53 has a hub portion 54 which may be clamped to the shaft portion 52. The cam member 53 is provided with a cam groove 55 formed adjacent its periphery. Directly below the member 53 on an enlarged portion 56 of the shaft 51 is a wheel member 57. Bushings 58 are disposed in the hub 59 of wheel member 57 and around shaft portion 56. The lower end of the hub portion 59 has a bevel gear 60 bolted thereto. This gear 60 is engaged by a bevel pinion 61. A thrust bearing 62 of the ball bearing type is disposed between gear 60 and the upper end of the sleeve 49. A housing portion 63 is formed integral with the upper portion of sleeve 49 and encloses gears 60 and 61. This housing can be filled with oil. It is provided with a removable cover 64.

The pinion 61 is keyed on the inner end of a shaft 65. This shaft 65 extends through a lateral extension 66 (Figure 2) formed on the housing 63. The outer end of this shaft 65 is rotatably mounted in a bearing 67 which is supported by the plate 46. The extreme outer end of the shaft 65 has a sprocket 68 keyed thereon. This sprocket 68 is driven by a chain 69 which also passes around a sprocket 70 which is keyed on the outer end of a shaft 71. This shaft 71 is disposed parallel to the shaft 65 and is rotatably carried by bearings 72 which are carried by a plate 73. This plate 73 is supported on the frame 4 (Figures 2 and 3) by the angle members 47 which support the plate 46. The plate 73 is disposed directly behind the plate 46, extending the full width of the frame 4 and slightly beyond the sides thereof.

As shown best in Figures 2 and 15, the shaft 71 is adapted to be connected to or disconnected from a shaft 74 by means of a jaw clutch 75 which may be operated in a suitable manner. The shaft 74 is driven by a variable speed gear unit 76. The unit 76 is supported on the plate 73 intermediate the ends thereof. The gear unit 76 also drives a shaft 77 extending from the opposite side thereof. A clutch 78 is provided for selectively connecting the shaft 77 to or disconnecting it from a shaft 79. This shaft 79 is supported like the shaft 71 and drives a shaft 80, which is similar to and supported like the shaft 65, through the medium of a chain and sprocket drive 81. This shaft 80 extends into a portion 82 of a housing 83 which is like the housing 63. Within this housing gears are disposed for driving a vertical shaft 84 which is identical with shaft 51. This shaft 84 may form a part of a unit exactly like

the unit 45 previously referred to. If the conveyer 1 is at the left of the apparatus, as shown in Figure 2, the parts of the unit 45 will be in position as indicated. However, if the conveyer 1 is at the opposite side of our apparatus, the members 53 and 57 may be removed from the shaft 51 and be mounted on the shaft 84 at the opposite side of the apparatus. When the unit 45 is in the position indicated, the clutch 75 will be engaged and the clutch 78 will be disengaged. However, if the unit 45 is at the opposite side of the apparatus, the clutch 78 will be engaged and the clutch 75 will be disengaged. The gear unit 76 is driven by means of a sprocket 85 and a chain 86. The chain 86 passes around a sprocket 87 keyed on the outer end of shaft 40 which is driven by motor 44.

The spotter wheel 57 will be rotated on the shaft 51 by means of the pinion 61 upon rotation of the shaft 65. It will be rotated in a counter-clockwise direction, as shown in Figures 2 and 5. As shown best in Figures 4 to 7, the wheel 57 carries an article-engaging member 88 at the outer end of each of the arms 89 of the wheel. Each article-engaging member 88 comprises a supporting member 90 which is pivoted to the arm 89 by means of a pivot pin 91. The member 90 has a flat surface at one side of the pivot point 91 to which a blade member 92 is bolted by bolts 93. The blade member 92 consists of a straight portion 94 and a curved portion 95 disposed substantially at right angles to each other. On the opposite side of the pivot point 91 the member 92 carries an upstanding roller 96. This roller 96 is disposed in the cam groove 55 of the member 53. It will be apparent that the member 90 is substantially in the form of a bell crank lever with the roller 96 supported on one end thereof and the member 92 supported on the other end thereof. The outer end of each of the arms 88 is curved and has a similarly curved article-engaging plate 97 secured thereto in upstanding position. The cam groove 55 is of such outline that as the wheel member 57 rotates relative to the cam member 53, the member 90 and the members 92 carried thereby will be swung about the pivot points 91.

As each of the article-engaging members 92 moves over the conveyer 1, the straight portion 94 thereof will be projecting radially from the wheel 57 and over the conveyer belt 1. When the member 92 is in this position, the portion 95 of member 92 will be in alignment with the two adjacent members 97. Thus, there will be no danger of articles passing between the arms 89 of the wheel. As the wheel continues to rotate, each of the members 90, as shown in Figure 5, will be swung about its pivot 91 in such a manner that both the portions 94 and 95 of the member 92 will be disposed practically within the periphery of the wheel 57. A curved guide member 98 is provided and has one end welded to a plate 99 (Figure 7). This plate 99 is secured to a second plate 100 which is fastened to an angle member 101. The plate 99 bridges the gap between the conveyer belt 1 and the conveyer belt 14. It is disposed at the same level as these belts and is provided with an extension 102 which extends over the curved part of the belt 14 as shown in Figure 7. The angle member 101 is carried on the upper end of an upstanding support 103. This support 103 has its lower end bolted to the outer end of the plate 46. The guide member 98 will be disposed parallel to the path of travel of the outer ends of the arms 89 of the wheel 57. It will

be understood that if the unit 45 is at the opposite side of our apparatus, the guide 98 and plate 99, together with the supporting structure, will be duplicated at that side of the apparatus.

It will be apparent that the conveyer 1 and the conveyer 3 will be rotating continuously. Also, the spotter wheel unit 45 will be operating continuously. As the glass articles are carried by the conveyer 1 to a point adjacent the spotter wheel, the portions 94 of the article-engaging members will be extended outwardly and will engage the rear surface of each successive article. The article will then engage the guide 98. The article will be pushed from the conveyer 1 onto the plate 99 by the cooperation of member 94 and guide 98, as shown in Figure 5. The article will finally be pushed by the portion 94 onto the conveyer belt 14. Thus, the spotter wheel unit will serve to transfer articles from the conveyer 1 to the conveyer 3. As each article is pushed onto the end of the conveyer unit 3, the member 90 of each article-engaging unit will be swung in such a manner that the portion 94 of the article-engaging member will be swung inwardly toward the center of the wheel 57 so that it will quickly move out of engagement with the article positioned on the belt 14. This will prevent the article from being shoved rearwardly off the conveyer 3. As each article-engaging member again moves to a position adjacent the conveyer 1, it will be swung in such a manner that the portion 94 will project over the conveyer 1. The conveyer 1 will travel at a comparatively high rate of speed. The unit 45 will operate at a comparatively high rate of speed. However, the conveyer unit 3 will operate at a comparatively low rate of speed. This will serve to position the articles on the conveyer unit 3 in closely spaced relationship. The speed of the units 45 and 3 can be controlled independently. The speed of unit 45 can be controlled by the variable speed gear unit 76 while that of the unit 3 can be controlled by the variable speed gear units 36 and 38.

The cam member 53, the wheel member 51 and the guide member 98 will be designed for operating on articles of a particular size. If different size articles are to be transferred by the unit 45, the members 53, 57 and 98 will be replaced with members suitable for that particular size article. The article-engaging portions 94 and 97 may be covered with felt or other soft material to prevent injury to the article.

It will be apparent that as the unit 45 feeds the articles onto the conveyer unit 3 in closely spaced relationship, the belt 14 will move these articles into position in front of the lehr. The articles will be assembled, therefore, as a row of closely spaced articles extending across the front of the lehr. The pusher bar apparatus which we shall now describe will engage the rear side of this row of articles and will shove off the belt 14 onto the conveyer belt 6. To bridge the gap between the belt 14 and the belt 6, a plate 104 is provided which extends for the full width of the belt 6. This plate 104 (Figure 2) is fastened to the forward beam 11 of conveyer unit 3 by means of screws 105.

The pusher bar mechanism is shown best in Figures 1 to 3 and 8 to 10. It comprises the pusher bar 106 which extends transversely of the frame 4 (Figure 1) and is slightly less in length than the width of the frame so as not to interfere in its movements with the side members of the frame. The pusher bar 106 has its ends bolted, as at 107, to the lower ends of bars

108. These bars 108 are disposed in contact with a pair of vertically disposed arms 109. The bars 108 are connected to the arms 109 by bolt and slot connections 110 so as to permit vertical positioning of the bar 106 on the arms 109. This adjustment is desirable to position the bar 106 to the proper distance above the belt 14, depending upon the size of the articles being loaded into the lehr.

10 The upper ends of the arms 109 are rotatably mounted on a shaft 111 adjacent the outer ends thereof. This shaft 111 is horizontally disposed and is carried within a sleeve 112 which serves to maintain the arms 109 properly spaced from each other. The shaft 111 carries grooved rollers 113 on its outer ends which operate on tracks 114. These tracks 114 have their main portions horizontally disposed and secured to beam members 115 which project from the frame 4 (Figure 3) and extend over the conveyer belt 6 of the lehr when our apparatus is properly positioned relative to the lehr. The beams 115 extend rearwardly the full depth of the frame 4. The tracks 114 have curved portions 116 joined to upstanding portions 117 at the rear ends thereof. For cooperating with the tracks 114, each of the members 115 supports on its inner surface a guide member 118 disposed parallel to the horizontal portion of the 20 cooperating track 114. This guide member 118 has a track section 119 pivoted thereto as at 120. This track section 119 extends downwardly and forwardly from the pivot point 120 and its forward and lower end rests on the upper edge 25 of the horizontal portion of the track 114. The lower end of each member 119 carries a removable and replaceable shock-absorbing rubber cushion 121. It will be noted from Figure 2 that the upper end of member 119 fits into the bifurcated forward end of member 118 so that the members 118 and 119 form a continuous track section. The member 118 is spaced above the 30 horizontal portion of track 114 a sufficient distance to permit the roller 113 to pass therebetween. Furthermore, the rear end of each guide 35 member 118 is spaced from the vertical portion 117 of tracks 114 to permit passage of roller 113 downwardly therebetween. It will be noted that the rear end of member 118 is curved, as at 122, to facilitate downward travel of the roller around the arm of this member.

The shaft 111 which carries the rollers 113 is adapted to be moved forwardly and then rearwardly. During the forward movement of the 40 shaft 111, the rollers will operate on the horizontal portions of the tracks 114 as shown best in Figure 10. As the rollers 113 move forwardly on the tracks 114, they engage the movable track sections 119 and swing them upwardly. The rollers will eventually move past the members 119, when the members 119 will again swing downwardly into contact with the tracks 114. Then the shaft 111, which carries the rollers 113, will begin to move rearwardly. This will cause the rollers 113 to travel up the inclined track section 119, which at this time will be at an approximately 45 degree angle relative to the horizontal section of tracks 114. The rollers 113 will ride up the sections 119 and onto the sections 118. They will eventually drop down between the rear ends 122 of members 118 and the vertical portions 117 of the tracks 114. They will be guided by the portions 117 downwardly to the curved portion 116 of the tracks 114. At this time the 45 shaft 111 will be moving forwardly so as to move

the rollers 113 forwardly and the rollers will again traverse the same path.

Thus, the shaft 111 will move forwardly along a horizontal path, upwardly and rearwardly along an inclined path, then rearwardly along a horizontal path spaced above the first-named horizontal path, and then downwardly and again forwardly. This will impart the same movement to the pusher bar 106. In other words, the pusher bar 106 will be moved through a continuous and closed path forwardly at one level, upwardly and rearwardly to another level, then rearwardly, and then downwardly to the original level where the movements will be repeated. This will serve to cause the pusher bar 106 to move behind a row of articles assembled in front of the lehr, as shown in Figure 10, horizontally into engagement with the row of articles to shove them from the belt 14 across plate 104 onto the lehr conveyor 6. Then, the pusher bar will be moved rearwardly and upwardly and then rearwardly at a higher level. The rearward movement in an inclined and then horizontal path will serve to cause the pusher bar 106 to miss the next row of articles being assembled in front of the lehr on the conveyor belt 14, as shown by the dotted arrows in Figure 10. The pusher bar 106 will then move down into its lowermost position behind the newly assembled row of articles.

During the described movements of the shaft 111 which carries the pusher bar supporting arms 109, the arms 109 will remain in substantially vertical position. Rearward swinging movement of the arms 109 about the shaft 111, during the time the bar 106 is pushing the row of articles from the belt 14 to the belt 6, is prevented by adjustable stop members, each consisting of a screw member 123 threaded into a sleeve 124 carried by a support 125. These screw members 123 engage the rear edges of the arms 109. The supports 125 are carried by rearwardly extending arms 126 which have their forward ends keyed to the spacer sleeve 112 which is rotatably mounted on the shaft 111. Thus, these arms 126 move with the shaft 111 and, consequently, with the arms 109. Thus, as the pusher bar pushes the articles, it will not swing rearwardly. If upon the upward and rearward movement of the pusher bar, it did engage the glass articles being assembled in front of the lehr, it can swing forwardly about the shaft 111.

In order to impart the described forward and rearward movement to the pusher bar, we provide a pair of sprocket chains 127 which are disposed adjacent opposite sides of the frame 4. Each sprocket chain passes around a forward sprocket 128 keyed to a transverse horizontal shaft 129 and a rear sprocket 130 keyed to a transverse horizontal shaft 131. The shaft 131 is disposed parallel to shaft 129.

The shaft 129 is rotatably carried by a pair of bearings 132 disposed adjacent the ends thereof. These bearings 132 are supported on a plate 133. This plate 133 is disposed between the beam members 115 and is supported by transverse angle members 134 which are secured to the members 115. The bearings 132 have guide portions 135 disposed on their lower ends which fit into guides 136 provided on the plate 133. The bearing members 132 are, therefore, adjustable rearwardly and forwardly on the plate 133 in the guides. To accomplish this adjustment and hold the bearings in adjusted position, adjusting screws 137 are provided. It will be apparent that with this adjustment, the distance between the shaft 129 and the

shaft 131 can be varied. This will vary the distance between sprockets 128 and 130. Consequently, the tension of the chains 127 can be adjusted readily.

Intermediate its ends, the shaft 131 has a sprocket 138 keyed thereon. This sprocket 138 is driven by a chain 139 which extends downwardly through an opening 140 (Figure 2) formed in the plate 133. The chain 139 passes around a sprocket 141 of a clutch unit 142. This clutch unit will be described in detail, subsequently, and is supported by a plate 143. This plate 143 is supported by angle members 144, carried by frame 4, substantially at the level of the conveyor unit 3. Thus, when the clutch 142 is engaged, the sprockets 130 will be driven and therefore the endless chains 127 will be driven.

The arms or bars 126 are pivotally connected to the chain 127 at oppositely disposed points indicated by the numerals 145. These two points are in alignment with each other. The arms or bars 126 are disposed outside the plane of the chains 127 and are free to pivot about the points 145. When the sprocket chains 127 are driven, the bars 126 will be pushed forwardly, will be moved upwardly and will then be moved rearwardly. This will move the shaft 111 and, consequently, the pusher bar 106 through the path previously described. During this movement, the pivot points 145 will travel through a path of the same outline as the endless chain 127. During this movement the rear ends of the bars 126 will pivot about the points 145 while their forward ends will pivot about the axis of shaft 111. Thus, it will be apparent that we move the pusher bar through the desired path by mechanical means only.

The clutch 142 is illustrated best in Figures 1, 3, 9, 13, 14 and 15. As previously indicated, this clutch includes a large sprocket 141. This sprocket 141 drives the chain 139. The sprocket 141 (Figure 13) is bolted by bolts 146 to a hub member 147. The hub member 147 is keyed to a shaft 148. This shaft 148 is rotatably mounted in ball bearing 149 supported on standards 149a which are bolted to the plate 143. Rotatably disposed on the shaft 148 by means of bushing 150 next to the hub member 147 is a hub member 151. This hub member 151 has keyed thereon, at its end adjacent hub 147, a ratchet wheel 152. At its opposite end the hub member 151 has a sprocket 153 disposed in surrounding relationship thereto and which is bolted by bolts 154 to flange 155 formed on the hub member 151. Suitable spacer collars 156 and 157 are provided on the shaft 148 to maintain these various members in spaced relationship. The sprocket 141 is spaced from the ratchet wheel 152, as indicated in Figure 13. The sprocket 141 carries adjacent its periphery a pivot pin 158. This pivot pin pivotally carries a pawl member 159. The pawl member 159 is positioned in the same plane as the ratchet wheel 152 by means of a spacer 160 disposed on the pivot pin 158. The pawl member 159 is disposed adjacent the periphery of the ratchet wheel 152 and is provided with a ratchet tooth engaging portion 161 on its one end. A sprocket chain 162 passes around the sprocket 153 and serves to drive it and the sprocket wheel 152 in a counter-clockwise direction. The members 152 and 153 will normally be driven continuously. These members will rotate with the hub 151 on the shaft 148. The pawl 159 will normally be held in the position indicated in Figure 14, out of engagement with the ratchet wheel 152. It will be held

in this position by means of a pin 163 which is in engagement with a cam portion 164 formed on the pawl member 159 at the end opposite to where the portion 161 is formed. Consequently, the sprocket 141 will normally be stationary while the members 152 and 153 will be rotated.

The pin 163 (Figure 13) is carried by a piston 165. This piston is mounted for axial movement in a cylinder 166 supported on a suitable support 167 which is bolted to the plate 143. The pin 163 is slidably mounted in an extension 168 of the cylinder which projects toward and closely adjacent to the pawl member 159. A spring 169 of the compression type normally forces the pin 163 outwardly so that the cam portion 164 of the pawl will engage it. A vent 170 is provided in one end of the cylinder 166, while an air inlet opening 171 is provided in the other end of the cylinder 166. When air is forced into the cylinder 166, the piston 165 will be moved to the left (Figure 13) against the action of spring 169. This will withdraw the pin 163 to a position out of engagement with the cam portion 164 of the pawl 159. Due to the fact that the weight of the portion of pawl 159 to the right of pin 153 (Figure 14) is greater than the weight of the portion thereof to the left of the pin, this will permit the pawl-engaging portion 161 of member 159 to drop downwardly into engagement with one of the teeth of member 152 which will be rotating in a counterclockwise direction. Consequently, the sprocket 141 will be rotated along with the member 152. In the meantime, the spring 169 will serve to return the piston 165 and the pin 163 to the original position indicated in Figure 13. The sprocket 141 will travel through one complete rotation and then the cam portion 164 of the pawl 159 will again engage the pin 163 which will be projected over the ratchet 152. This will cause the pawl 159 to be swung around its pivot 158 so that the ratchet-engaging portion 161 thereof will be withdrawn from engagement with the ratchet 152. Thereafter, the ratchet 152 will rotate without rotating the sprocket 141. Thus, the sprocket 141 will be rotated through one complete revolution each time the pin 163 is withdrawn from engagement with the member 159. Rotation of the sprocket 141 will cause the shaft 148 to rotate in its bearings 149. Rotation of the sprocket 141, as indicated, will produce rotation of the sprocket 138 (Figures 2, 3 and 15). This will produce movement of the chains 127 to such an extent that the pivot points 145 will travel through one complete path of an outline like that of the chains 127.

The sprocket chain 162 which drives the sprocket 153 is driven by means of a sprocket 112 (Figure 15) which is keyed on the end of a shaft 113 that extends from the variable gear unit 36. The chain 162 passes downwardly through an opening 143a which is formed in the plate 143. This opening also permits the sprocket 141 to extend below the plate. It will be apparent that the driving mechanism for the clutch unit 142 and the driving mechanism for the conveyer unit 3 will always have a predetermined timed relationship. Any variations in the speed of the conveyer unit 3 will result in a corresponding change in the speed of the driving element 152 of the clutch. This is due to the fact that both of these units are driven by the same gear unit 36. Consequently, the movement of the pusher bar will always be in properly timed relationship to the movement of the belt 14 of the conveyer unit 3.

Flow of air to the cylinder 166 to move the

piston 165 is accomplished by means of an air line 174, which is connected to the inlet port 171. This line 174 (Figures 11, 12 and 15) is connected to a valve 175. This valve 175 is supported by a support 176 which is secured to the plate 143. The valve 175 (Figure 11) comprises a valve stem 177 which has a head 178 formed thereon. This head is adapted to cooperate with the seat 179. A spring 180 normally maintains the head 178 on its seat 179. The line 174 is connected to an opening 181 in the valve casing which is in communication with a chamber 182 formed therein. An air inlet pipe 183 is connected to the valve casing and is in communication with chamber 184 formed therein. When valve head 178 is unseated, air from the main supply line 183 is allowed to flow to the line 174 and, consequently, to the clutch-actuating cylinder 166.

The valve 175 is adapted to be actuated at proper intervals to supply a puff of air to the cylinder 166. It is actuated by means of a pivoted cam lever 185 which is pivoted at its upper end, as at 186, to the support 176. This lever 185 has a lower flat surface 187 in engagement with the outer end of pin 177 and has an outer cam portion 188 at its lower end. The lever 185 is normally vertically disposed. A timer drum 189 (Figures 11 and 12) is provided and has a pair of timing disks 190 mounted thereon. One of these disks operates the valve 175. This disk has a T-shaped slot 191 formed in its periphery in which a similarly shaped screw member 192 is disposed. This screw member projects radially from the slot and carries a button 193. The button 193 may be set at any position around the circumference of the disk 190. It will be apparent that when the disk is rotated in a counterclockwise direction (Figure 11) the button 193 will strike the cam portion 188 of lever 185 at intervals and will force the stem 177 inwardly unseating the valve head 178 and allowing a puff of air to reach cylinder 166. However, as soon as button 193 passes cam portion 188, the valve head 178 will again be seated and will shut out the flow of air to the cylinder 166. The puff of air will move the piston 165 and withdraw the pin 163, as previously indicated. When the valve 175 is closed, the piston 165 will be returned to its original position by spring 169, there being sufficient leakage of air from the right-hand end of cylinder 166, around pin 163, to permit this.

The timer disks 190 are keyed to a shaft 194. This shaft 194 is rotatably mounted on the support 176. A hub member 195 is also keyed to the shaft. This hub member has a large sprocket wheel 196 bolted thereto. Sprocket wheel 196 is driven by a sprocket chain 197 which passes around a small sprocket 198 which is carried by the shaft 26 (Figures 11, 12 and 15). In order to adjust the tension of the chain 197, we provide a lever 199. This lever carries a pin 201 on one end, which is mounted in a clamping yoke 200 secured to plate 143. The free end of the lever carries a sprocket pinion 202 which engages the chain 197. Swinging the lever 199 upwardly or downwardly and clamping it in position will adjust the tension of the chain.

As previously indicated, when the rollers 113 of the pusher bar supporting structure reach the extent of their rearward travel, they drop off the guides 118 and downwardly onto the tracks 114. In order to eliminate shock on the pusher bar and its supporting structure when the rollers drop in this manner, we provide a substantially hori-

zontally disposed shock plate 203. This plate 203 (Figure 10) has its rear end pivoted, as at 204, to the plate 133 by means of upstanding bearing members 205. The pivot point 204 will be located sufficiently high to permit the required swinging movement of the plate 203 in a vertical plane without interference with plate 133. The plate 203 is located between chains 127 and extends forwardly to a point well beyond the rear end of the guides 118. The forward end of this plate is turned downwardly, as indicated at 206. When the rollers 113 drop downwardly, the spacer 112, which is disposed on shaft 111, will strike this plate 203.

A vertically disposed cylinder and piston unit 207 is supported on the front of the frame 4 below the forward end of the plate 203. The cylinder has a piston 208 mounted therein. This piston has an upstanding piston rod 209 which is pivotally connected to the lower surface of the plate 203, as at 210. An air line 211 leads into the lower end of the unit 207. An adjustable check valve 212 is provided in this line 211. When the rollers 113 drop off the members 118, the forward end of the plate 203 will have been swung upwardly to its uppermost position, by means of air supply to the unit 207 through the line 211. As the member 112 strikes the forward end of the plate, the plate will gradually settle downwardly, the gradual escape of air from unit 207 past check valve 212 permitting this. Thus, the plate 203 will serve as a shock absorber.

The line 211 is connected to a valve 175a which is exactly the same as the valve 175 previously described. This valve 175a will be actuated by one of the timer disks 190. Since the timer drum is driven by the shaft 26, the speed thereof will be adjustable by the unit 36. This unit 36 controls the speed of the drive for the conveyer unit 3 and the clutch 142, as previously described, as well as the timer unit. Thus, all of these various units will operate in a predetermined timed relationship. Any variation in the speed of one unit will result in the variation of the speed of the other units.

In Figures 16 and 17, we show different means for feeding the articles from the conveyer unit 1 to the conveyer unit 3. This means comprises a rotatable table unit 45a which is driven substantially the same as the spotter wheel unit 45 and which can be mounted at either side of our apparatus, depending upon the position of the conveyer unit 1. This table 45a is disposed at the same level as the conveyers 1 and 3. It fits over the upper end of a shaft 51a and is provided with a cap 51b. This cap carries a screw 51c which engages the upper end of shaft 51a and by means of which the level of table 45a may be accurately adjusted. Around the hub of member 45a a pulley member 51d is provided. The shaft 51a is rotatably mounted in a sleeve 49a. A gear 60a rests on the upper end of this sleeve and is splined to member 45a, as at 60b. The gear 60a is driven substantially the same as gear 60 previously referred to. A belt 51e, formed of an endless coil spring, passes around pulley 51d and around a small pulley 51f disposed over conveyer 3. This pulley 51f is carried on the outer end of an arm 51g which carries a pin on its other end rotatably disposed in a clamping collar 51h. The member 51g is provided with an adjusting handle 51i. A curved guide 98a is provided which extends along conveyer 1, substantially tangential to member 45a, and then over the conveyer 3. This guide has one end pivoted to unit 1 as at 98b

and its other end adjustably connected to unit 1 by a pin and slot connection 98c. The guide 98a may be swung toward or away from member 51d and held in adjusted position. The belt 51e may be adjusted toward or away from member 98a by swinging lever 51b, by means of handle 51i, around its pivot point to move the pulley 51f into the desired position. The clamp 51h may be tightened to hold it in this position. These adjustments provide means for adjusting the unit 45a in accordance with different size articles. If the articles vary too much in size, the member 51d may be replaced with a different size member.

It will be apparent that the articles will be fed from the conveyer 1 onto the rotating table 45a and then onto the conveyer 3. The moving belt 51e will aid in moving the articles from table 45a to conveyer 3 and will prevent tipping of the articles due to their contact with guide 98a.

It will be apparent from the above description that we have provided a lehr loader of such a nature that it can readily handle glassware of practically all shapes and sizes. It is of such a nature that the mechanism for imparting the movement to the pusher bar is entirely mechanically operated thereby requiring a minimum amount of air which is used merely as a control means and not as power means for operating the pusher bar.

Various other advantages will be apparent from the preceding description, the drawings and the following claims.

Having thus described our invention, what we claim is:

1. A lehr loader of the pusher bar type comprising a supporting frame, a cross conveyer mounted on said frame, means carried by the frame for driving said cross conveyer continuously, a pusher bar extending longitudinally of said conveyer, means for supporting said pusher bar for movement in a closed path transversely of the conveyer whereby the bar will move behind a row of articles and push them transversely off the conveyer, said means including trackways supported by the frame and rollers which support said pusher bar and operate on said trackways, said trackways each comprising a horizontal lower portion and a horizontal upper portion disposed in spaced relationship, said upper portion being shorter than the lower portion, a pivoted track section having its upper end pivoted to the forward end of said upper portion and its lower end resting on the lower portion, said lower portion having a vertical section adjacent its rear end spaced from the rear end of the upper portion, means including endless chains for moving said rollers along said trackways, and means for connecting said rollers to said chains.

2. A lehr loader of the pusher bar type comprising a supporting frame, a horizontally disposed cross conveyer mounted on said frame adjacent the front end thereof, means carried by the frame for driving said cross conveyer continuously, a horizontally disposed pusher bar extending longitudinally of said conveyer, a carriage from which said pusher bar is suspended, said carriage including rollers, trackways supported on said frame and extending over said cross conveyer at a point spaced a substantial distance thereabove, said rollers operating on said trackways, said trackways comprising horizontal lower portions and horizontal upper portions disposed in spaced relationship, the upper portions being shorter than the lower portions,

pivoted track sections secured to the forward ends of said upper portions and having their lower ends resting on said lower portion, said pivoted sections normally being supported in inclined relationship, said lower portions having vertical portions adjacent their rear ends spaced from the rear ends of said upper portions, means for moving said carriage in such a manner that the rollers travel forwardly along said lower portions, beyond said pivoted sections, up said inclined sections and then downwardly off said upper portions and along the vertical portions of the lower portions, said means comprising endless chain members supported on said frame at substantially the same level as said trackways and behind said trackways, and pivoted links connecting said carriage to said chains.

3. A lehr loader according to claim 2 wherein drive mechanism is provided for driving said chains, said drive mechanism including a clutch.

4. A lehr loader according to claim 2 wherein drive mechanism is provided for driving said chains, said drive mechanism including a clutch, and a fluid-operated unit for engaging said clutch.

5. A lehr loader according to claim 2 wherein drive mechanism is provided for said chains, said drive mechanism including a clutch, a fluid-operated unit for engaging said clutch, and timing mechanism for operating said last-named means at predetermined intervals.

6. A lehr loader according to claim 2 wherein drive mechanism is provided for said chains, said drive mechanism including a clutch, and means for simultaneously changing the speed of said chain drive mechanism and said conveyer drive mechanism.

7. A lehr loader according to claim 2 wherein drive mechanism is provided for said chains, said drive mechanism including a clutch, a fluid-operated unit for engaging said clutch, a timing unit for operating said last-named means at predetermined intervals, driving mechanism for said unit, and means for simultaneously adjusting the speed of said conveyer-driving mechanism, said chain-driving mechanism and said timing unit driving mechanism.

8. A lehr loader according to claim 2 wherein cushioning means is provided for said carriage to decrease shock when said rollers drop off the upper sections of said trackways, said cushioning means comprising a shock plate pivoted to said frame for vertical movement, said shock plate being in such position that the carriage will strike the forward end thereof when it drops from said track sections, and means for holding said plate in an upper position but gradually permitting downward movement thereof.

9. A lehr loader according to claim 2 wherein cushioning means is provided for said carriage to decrease shock when said rollers drop off the upper sections of said trackways, said cushioning means comprising a shock plate pivoted to said frame for vertical movement, said shock plate being in such position that the carriage will strike the forward end thereof when it drops from said track sections, and a cylinder and piston unit for moving said plate to its upper position but gradually permitting settling thereof, and means for controlling the supply of fluid to said unit.

WILLIAM L. McNAMARA.
JAMES McFEE.
